Primary Examiner — Ramzi Almatrahi(74) *Attorney, Agent, or Firm* — Young Basile Hanlon & MacFarlane, P.C.(57) **CLAIM**

The ornamental design for a camera display mount, as shown and described.

DESCRIPTION

FIG. 1 is a top, rear, and left side perspective view of a camera display mount showing our new design in a first configuration;

FIG. 2 is a top, front, and right side perspective view thereof, shown in a second configuration;

FIG. 3 is a rear elevation view thereof, shown in the first configuration;

FIG. 4 is a front elevation view thereof;

FIG. 5 is right side elevation view thereof;

FIG. 6 is a left side elevation view thereof;

FIG. 7 is a top plan view thereof; and,

FIG. 8 is a bottom plan view thereof.

The broken lines depict portions of the camera display mount in which the design is embodied that form no part of the claimed design. The dash-dot broken lines denote the boundary of the claim and form no part of the claimed design.

1 Claim, 8 Drawing Sheets(56)
